UNITED STATES PATENT OFFICE

2,322,868

TOOLHOLDER

Bronislaw Misiura, Duquesne, Pa.

Application September 18, 1941, Serial No. 411,412

5 Claims. (Cl. 51—96)

This invention relates to tool holders and, particularly to an improved tool holder for holding chisels and the like while grinding the same.

The tool holder of the present invention is especially adaptable for use with a grinder attachment of the type disclosed in the patent application of William Van Triest, Serial No. 366,749, filed November 22, 1940.

It is the general object of the present invention to provide an improved tool holder for holding chisels and the like while the same are being ground, which is simple and inexpensive in its construction and, at the same time, one which is efficient and effective in its use.

It is another object of the invention to provide an improved tool holder for holding chisels and the like, while the same are being ground, which is easy and convenient to use and securely holds the tool to be sharpened, and one which is safe in its use, thereby eliminating any danger of injury to the operator or other workmen in the vicinity of the grinding operation.

It is a further object of this invention to provide an improved tool holder which is adapted to be incorporated with a grinder attachment of the class described so as to obtain uniform grinding and sharpening of the chisels or other tools.

Various other objects and advantages of this invention will become more apparent during the course of the following specification and will be particularly pointed out in the appended claims.

In the accompanying drawings there is shown, for the purpose of illustration, one embodiment which my invention may assume in practice.

In these drawings:

Figure 1 is a plan view of a grinder attachment, showing the application of the tool holder of my invention thereto;

Figure 2 is an enlarged plan view of the tool holder, partly in section;

Figure 3 is a sectional view taken on the line III—III of Figure 2; and

Figure 4 is a plan view of the body member of the tool holder, showing the stationary jaw thereof.

For the purpose of illustration, the improved tool holder of my invention is shown incorporated with the type of grinder attachment hereinbefore referred to. Such an attachment is designed to be mounted on the frame or stationary portion of a grinder with the attachment being positioned adjacent the wheel 2 of the grinder and in front thereof. The attachment consists generally of a carriage 3 slidably mounted on the base 4 for movement toward and away from the

periphery of the grinding wheel 2, as by means of a screw 5 having a handwheel 6. A gib is provided at 7 for fixing the slidable carriage 3 in the base. There is rotatably mounted on the base an attachment head 8 which is provided with means comprising a pair of grinding supports A and B designed to be positioned opposite the grinding wheel 2 by rotation of the head 8. The support B includes a radially extending arm 9 integral with the head 8 and terminating in a transverse hub or journal portion 10 in which the improved tool holder, in accordance with the present invention, is mounted. There is arranged with the head 8 a handle 11 which preferably extends radially therefrom on the side of the head away from the arm 9 and toward the operator.

The improved tool holder of my invention, as shown in Figures 2, 3, and 4 of the drawings, consists of a longitudinally extending hollow cylindrical body member or housing 12 having a stud shaft 13 arranged therewith which is journaled in the transverse hub or journal portion 10 of the arm 9 and supported by the ball bearings 14. The upper or outer end of the body member 12 has a substantially U-shaped groove 15 arranged therein for receiving the chisel or other tool to be ground. There is arranged in the groove 15, preferably a transversely extending hardened steel insert member 16 having a U-shaped serrated edge 17 which is adapted to act as a stationary jaw. The insert member 16 is held in position in the body member 12 preferably by means of a pin 18.

In the upper or outer end of the body member 12 forwardly of the insert member 16 there is reciprocably arranged a head 19 which is adapted to act as a movable jaw having a transversely extending hole 20 arranged therethrough in which the chisel or tool to be ground is adapted to lie. In the upper side of the head 19 centrally thereof and the hole 20 therethrough, there is mounted, preferably, a hardened steel insert member 21 having a knife edge 22 which is adapted to engage with the shank of the chisel, preferably at two points, as shown in Figure 3. The insert member 21 is held in the head 19 preferably by means of a pair of pins 23.

There is positioned within the body member or housing 12 preferably a tension coil spring 24 having one end thereof preferably screwed onto the inner end of head 19 at 24a and the other end screwed onto the outer side of a threaded nut 25 at 24b, which, in turn, is screwed onto a cap screw 26 arranged through the lower or inner

end of the body member 12 for adjusting the spring tension.

There is pivotally mounted on a pin 27 arranged between a pair of outwardly extending lugs 27a, carried on the side of the body member 12, a lever-like handle member 28. There is integrally arranged with the handle member 28, an arm-like portion 29 which extends through an opening 30 in the side of the body member 12 and preferably has an enlarged head portion 31 which fits into a slot arranged in the head 19 just above the inner end of the spring 24.

On the outer end of the stud shaft 13 beyond the journal portion 10 of the arm 9 there is arranged a nut 32 and an angular-shaped chisel guide or support 33 which is adapted to support the outer end of the chisel or tool to be ground. The chisel guide 33 preferably has a slot or groove 34 arranged in the top surface thereof in which the tool or chisel is adapted to lie. A nut 35 preferably is provided on the extreme end of the stud 13 for holding the chisel guide 33 securely in position thereon for rotatable movement therewith.

The chisel or tool C to be ground is positioned in the tool holder in the following manner. The housing or body member 12 is gripped and the lever-like handle 28 forced inwardly toward the housing about its pivotal connection with the pin 27. Such movement of the handle 28 forces the head 19 outwardly from the end of the body member due to the action of the arm-like portion 29 and the enlarged head portion 31 carried thereby against the action of the tension spring 24. While the head 19 is held in such outer position, the chisel or other tool C to be ground is inserted through the opening 20 in the head and arranged in the groove 15 of the body member so that the inner end of the chisel properly rests in the slot 34 carried by the chisel guide 33 as shown in Figure 1 of the drawings.

When the chisel has been properly positioned in the tool holder, the lever-like handle 28 is released and the head 19 is moved inwardly into the body member due to the action of the spring 24. The chisel is then securely positioned in the tool holder and ready to be ground. It will be seen that the front end of the chisel is supported by the chisel guide or support 33 and that the rear end of the chisel is supported and gripped by the serrated edge 17 of the insert member 16. To one side of the insert member 17, and on the opposite side thereof between the chisel guide 33 and the insert member 16, the chisel is gripped by the knife edge 22 of the insert member 21 carried by the head or movable jaw 19. It will be understood that the head 19, together with the insert member 21 carried thereby, is held in clamping position solely by the tension coil spring 24. The degree of tension of the coil spring 24 may be adjusted by means of the cap screw 26.

The body member or housing 12 is also adapted to act as a handle which is moved about its pivotal connection in the journal portion 10 of the arm 9 so that the chisel is moved to grinding position in front of the wheel as shown in Figure 1 of the drawings.

As the grinding attachment is oscillated by means of the handle 11 carried thereby, the tool holder is rocked up and down on the stud shaft 13, thus grinding the back of the chisel on the face of the grinding wheel.

For the purpose of limiting the grinding movement, a stop 36 is provided on the carriage 3 adapted to be engaged by a coacting stop 37 of the

head 8, preventing rotating movement of the chisel on the wheel 3 rearwardly along the heel portion beyond a desired point thereof.

While I have shown and described one specific embodiment of my invention, it will be understood that this embodiment is merely for the purpose of illustration and description and that various other forms may be devised within the scope of my invention, as defined in the appended claims.

I claim:

1. A device for holding a chisel or a similar tool while sharpening the same by means of a grinding wheel, comprising a supporting member, a stud shaft mounted on said supporting member for rotatable movement relative thereto, a tool supporting and clamping means arranged on said shaft for supporting the inner end of the tool to be sharpened, said clamping means consisting of a longitudinally extending hollow body member extending substantially perpendicular to said shaft and having a clamping member arranged therein which is adapted to clamp securely the tool, resilient means arranged within said body member for moving automatically said clamping member to its clamped position, means for moving said clamping member against the action of said last mentioned means to its unclamped position, and means arranged on said shaft for supporting the outer end of the tool, said body member adapted to act as a handle portion whereby the shaft together with the inner tool supporting and clamping means and the outer tool supporting means carried thereby and the tool to be sharpened may be oscillated relative to said supporting member and the grinding wheel while the tool is being sharpened.

2. A device for holding a chisel or a similar tool while sharpening the same by means of a grinding wheel, as defined in claim 1, wherein the clamping member includes a jaw-like portion which is adapted to cooperate with a similar jaw-like portion carried by the body member whereby the tool to be sharpened is securely clamped therebetween.

3. A device for holding a chisel or a similar tool while sharpening the same by means of a grinding wheel comprising a supporting member, a stud shaft mounted on said supporting member for rotatable movement relative thereto, a tool supporting and clamping means arranged on said shaft for supporting the inner end of the tool to be sharpened, said clamping means consisting of a longitudinally extending hollow body member extending outwardly from said shaft, said clamping member having a movable jaw-like portion carried thereby which is adapted to cooperate with a similar jaw-like portion carried by said body member to securely clamp the tool to be sharpened therebetween, resilient means for moving automatically said movable clamping portion to and maintaining the same in its clamped position, means for moving said movable clamping portion to its unclamped position against the action of said last mentioned means whereby the tool may be inserted or removed from between said jaw-like portions, and means arranged on said shaft for supporting the outer end of the tool, said body member adapted to act as a handle portion whereby the shaft together with the clamping means and the outer tool supporting means carried thereby and the tool to be sharpened may be oscillated relative to said supporting member and the grinding wheel while the tool is being sharpened.

4. A device for holding a chisel or a similar

tool while sharpening the same by means of a grinding wheel comprising a supporting member, a stud shaft mounted on said supporting member for rotatable movement relative thereto, a tool supporting and clamping means arranged on said shaft for supporting the inner end of the tool to be sharpened, said clamping means consisting of a longitudinally extending hollow body member arranged substantially perpendicular to said shaft, a clamping member reciprocably arranged in and extending outwardly from one end of said body member, said clamping member having a hole arranged therethrough with the axis thereof disposed substantially parallel to said shaft and through which the tool is adapted to be inserted, a tension coil spring arranged within said body member having one end thereof connected to the inner end of said clamping member whereby the same is tended to be moved thereinto, said clamping member through the action of said spring adapted to maintain the tool against the end of the body member when the tool is positioned in the hole through said clamping member, means arranged on the opposite end of said body member for adjusting the tension of said coil spring, a lever-like handle member pivotally attached to said body member having a portion thereof extending thereinto into engagement with said clamping member, said lever-like member adapted to move said clamping member against the action of said coil spring whereby the tool may be positioned in or removed from the hole therethrough, and means arranged on said shaft for supporting the outer end of the tool, said body member adapted to act as a handle portion whereby the shaft together with the clamping means and the outer tool supporting means carried thereby and the tool to be sharpened may be oscillated relative to said supporting member and the grinding wheel while the tool is being sharpened.

5. A device for holding a chisel or a similar tool while sharpening the same by means of a grinding wheel comprising a supporting member, a stud shaft mounted on said supporting member for rotatable movement relative thereto, a tool supporting and clamping means arranged on said shaft for supporting the inner end of the tool

to be sharpened, said clamping means consisting of a longitudinally extending hollow body member arranged substantially perpendicular to said shaft, a clamping member reciprocably arranged in and extending outwardly from one end of said body member, said clamping member having a hole arranged therethrough with the axis thereof disposed substantially parallel to said shaft and through which the tool is adapted to be inserted, 10 a tension coil spring arranged within said body member having one end thereof connected to the inner end of said clamping member whereby the same is tended to be moved thereinto, said clamping member through the action of said spring adapted to maintain the tool against the end of the body member when the tool is positioned in the hole through said clamping member, means arranged on the opposite end of said body member for adjusting the tension of said coil spring, a 15 lever-like handle member pivotally attached to said body member having a portion thereof extending thereinto into engagement with said clamping member, said lever-like member adapted to move said clamping member against the action of said coil spring whereby the tool may be positioned in or removed from the hole therethrough, and means arranged on said shaft for supporting the outer end of the tool, said body member adapted to act as a handle portion 20 whereby the shaft together with the clamping means and the outer tool supporting means carried thereby and the tool to be sharpened may be oscillated relative to said supporting member and the grinding wheel while the tool is being sharpened.

BRONISLAW MISIURA.
